UNITED STATES PATENT OFFICE.

HARRY JOSEPH HICK, OF ALLIANCE, OHIO, ASSIGNOR TO THE McCASKEY REGISTER COMPANY, OF ALLIANCE, OHIO, A CORPORATION OF OHIO.

FILING APPLIANCE.

1,293,773.

Specification of Letters Patent. Patented Feb. 11, 1919.

Application filed November 30, 1917. Serial No. 204,519.

To all whom it may concern:

Be it known that I, HARRY JOSEPH HICK, a citizen of the United States, residing at Alliance, in the county of Stark and State 5 of Ohio, have invented certain new and useful Improvements in Filing Appliances, of which the following is a specification.

The invention relates to an appliance for filing time cards, cost coupons, sales bills 10 and other similar papers required for keeping industrial and commercial records, of the type composed of series of hinged holders mounted in a case or cabinet; and the object of the improvement is to operatively 15 combine two series of such holders, one above the other in the same case, in such a manner that the holders in the upper series are normally in upright position and the holders of the lower series are normally 20 in reclined position, and that an operation of the upper series into reclined position, automatically swings the lower series underneath the upper series.

Other objects of the improvement relate 25 to the method of mounting and carrying each series of holders and of controlling and counterbalancing the operation thereof one by the other and also on the gravity principle.

30 A preferred embodiment of the invention thus outlined in general terms is illustrated in the accompanying drawings forming part hereof, in which—

Figure 1 is a front elevation of the appliance showing a few of the upper series 35 of holders in upright position and the remainder of the upper series and all of the lower series of holders in reclined position;

Fig. 2, a section of the case on line 2—2, 40 Fig. 1, showing the holders in side elevation and illustrating the operation of the upper series of holders;

Fig. 3, a similar section and elevation 45 illustrating the operation of the lower series of holders;

Fig. 4, a similar section and elevation showing the two series of holders in normal 50 position for operation;

Fig. 5, a similar section and elevation 55 showing all the holders of the upper series swung into reclined position and the lower series swung under the upper series;

Fig. 6, a detached perspective inside view 60 of one-half the case, the carrier frame for supporting the upper series and guiding

the lower series of holders, and the swinging support for the lower series of holders;

Fig. 7, a fragmentary perspective view 60 showing the pivot pin on the lower corner of the foremost holder of each series; and

Fig. 8, a detached perspective view showing the guide pivot on the lower corner 65 of the rearmost holder of each series.

Similar numerals refer to similar parts 70 throughout the drawings.

The case may be composed of the base or bottom 1, the back wall 2, and the side walls 3; and the upper ends of the back and side walls may be connected together at the rear 75 of the case by means of the top plate 4, thus leaving the front and forward portion of the top open for access to and operation of the upper and lower series of holders 5 and 5^a; although it is evident that the top and front can be closed by a swinging or sliding 80 lid and door, not shown, as may be desired, to completely incase the holder when swung into the position shown in Fig. 5.

The carrier frame for the lower series of 85 holders is preferably composed of the back wall 6 and the side walls 7, and is mounted for swinging forward and rearward in the case by being pivoted at 8 to the lower ends of the parallel pendent links 9 having their upper ends pivoted at 10 to the side 90 walls of the case, a pair of such links being provided at each side of the holders.

A supporting bearing 11 is formed or secured in each upper rear corner of the carrier frame, for the pivot pins 12 which protrude laterally from the lower corners of the foremost holder 5' of the upper series; and a swinging support is provided for the 95 holders 5^a of the lower series which is preferably composed of a pair of pendent links 13 and 13' having their upper ends pivoted at 14 near the upper edge and on the outer side of each side wall 7 of the carrier frame, and having their lower ends yoked together by connecting bars 15, above which connecting bars a longitudinal angle bar 16 is 100 pivoted on each side to the inner side of the lower end of the links 13 and 13' of each pair.

At the rear end of each angle bar 16 is 105 formed or secured a supporting bearing 11^a for the pivot pin 12^a which protrudes laterally from each corner at the rear end of the lower holder 5^a of the lower series, and the inturned flanges of these bars form 110

shelves upon which the ends of the lower holder of the forward series rest for supporting this holder and the superposed holders of the lower series when the same 5 are rotated into normal reclined position. The rear link 13 of each pair is preferably made a little longer than the forward link 13', thus slightly elevating the forward ends of the lower holders of the lower series 10 so that the upper holders of the series will normally be in a horizontal plane.

On each side of the case, and on each side of the carrying frame, and near the rear wall thereof, is formed or secured a channel 15 guide 17 for the guide pivots 18 which protrude laterally from the hinged ends of the rearmost leaf 5" and 5'" of each series; and the rear flanges 19 of these channels are extended in width to form an abutment for 20 the side edges of the rearmost leaf to stop the same from swinging rearward beyond the channel guide.

The hinged connections 20 between the lower ends of the upper series and the rear 25 ends of the lower series, as shown in Fig. 2, space the hinged ends of the holders slightly apart and the upper ends of the channel guides and abutments are preferably inclined slightly forward so that when the 30 leaves in each series are collocated into upright position, the foremost leaf 5' and 5'" will stand upright substantially in a vertical plane, as shown in Fig. 3.

When the holders of the upper series are 35 in normal upright position, as shown in Figs. 3 and 4, the lower ends of the pendent links 9 are swung forward from their upper ends, being held in this position by engagement of the pivot pins 12 on the hinged ends 40 of the foremost holder 5' of the upper series with the supporting bearing 11 near the upper rear corners of the oscillating carrier frame, and the tendency of the pendent links to swing rearward, by reason of the weight 45 of the lower series of holders carried thereby, supplements the weight of the other leaves in the upper series, in holding the foremost leaf thereof in upright position, and also assists in elevating the rearmost 50 leaves until the links pass the vertical portion, after which the tendency of the pendent links to swing forward, by reason of the weight of the lower series of holders, assists in elevating the free ends of the reclined 55 holders in the upper series, after they have been started upward.

In this relation of the parts, the holders of the lower series may be swung upward, singly or collectively, from their normal reclined position shown in Fig. 4, into an upright position shown for all but two of the holders in Fig. 3; and in this movement, the supporting bars 16 swing forward with the lower ends of the pendent links 13 from a 60 normal rearward position, shown in Figs. 2

4 and 5 in which the lower ends of these links are inclined a substantial distance rearward from their upper ends, to a forward position, when all the lower holders are swung into upright position, as shown for 70 most of these holders in Fig. 3, when the lower ends of the pendent links 13 are inclined forward from their upper ends; and it is evident that the counterbalancing effect of these links serves to assist the operation 75 of the lower series of leaves, in substantially the same manner as described above for the upper series.

I claim:—

1. A filing appliance including an oscillating carrier, a series of holders on the oscillating carrier, a swinging support depending from the oscillating carrier, and a series of holders on the swinging support. 80

2. A filing appliance including an oscillating carrier, a series of holders on the oscillating carrier, a swinging support depending from the oscillating carrier, and a series of holders on the swinging support, pivot bearings on the carrier and the support for 90 the foremost holder of the respective series, a guideway adjacent to the carrier for the rearmost holder of one series and a guideway in the carrier for the rearmost holder of the other series. 95

3. A filing appliance including an oscillating carrier, a series of holders on the oscillating carrier, a swinging support depending from the oscillating carrier, and a series of holders on the swinging support, pivot 100 bearings on the carrier and the support for the foremost holder of the respective series, a guideway adjacent to the carrier for the rearmost holder of one series and a guideway in the carrier for the rearmost holder of the other series, said guideways forming 105 stops for the rearmost holder of the respective series.

4. A filing appliance including a carrier pivoted to pairs of pendent links, a series of 110 hinged holders on the carrier, a support pivoted to pairs of pendent links depending from the carrier, and a series of hinged holders on the support, pivot bearings on the carrier and the support for the hinged 115 ends of the foremost holders of the respective series, a guideway adjacent to the carrier for the hinged end of the rearmost holder of one series, and a guideway on the carrier for the hinged end of the rearmost 120 holder of the other series, the pendent links moving both forward and rearward from a vertical position in the operation of the respective series of holders.

5. A filing appliance including pairs of 125 pendent links pivotally supported at their upper ends, a horizontal support pivoted to the lower ends of the links, a series of hinged holders bodily carried by the horizontal support having the hinged end of the foremost 130

holder pivoted thereon, and a guideway adjacent to the holders engaging the rear end of the rearmost holder for swinging the pendent links forward and rearward from a vertical line in the operation of the holder.

6. A filing appliance including an oscillating carrier, a swinging support depending from the carrier, pivotal bearings on the carrier and on the support, upright guideways adjacent to the carrier and in the carrier, a

series of hinged holders having pivot pins on the hinged end of the foremost holder, resting in the carrier bearings and guide pivots on the hinged end of the rearmost holder, operating in the adjacent guideways, 15 and a second series of hinged holders having like pivot pins resting in the support bearings, and like guide pivots operating in the carrier guideways.

HARRY JOSEPH HICK.
